CAN FILLING MACHINE

Robert Luthi, Newark, N. J., assignor to American Can Company, New York, N. Y., a corporation of New Jersey

Application November 28, 1933, Serial No. 700,156

22 Claims. (CL. 226—98)

The present invention relates broadly to vacuum syruping food products and has particular reference to an apparatus for subjecting the interior of the can to a vacuum to remove air not only from the can, but also in large part from the cells of the product and then adjusting the vacuous condition for the syrup fill so that when syruping takes place the syrup fills the can only to the height desired at the same time protecting the can wall against collapse or distortion.

The present invention contemplates the association of mechanical devices for receiving cans, partially filled with solid contents such as fruit or other cellular products, and conveying these cans into filling position where a part of the exterior can wall is supported and protected against collapse or distortion, while the interior of the can, as well as the fruit cells, are vacuumized, preferably with a high vacuum and syrup is then filled into the can to a predetermined height.

A simple and desirable manner of vacuum filling contemplated in this invention is the step of vacuumizing the fruit filled can at a maximum degree of vacuum regardless of the amount of syrup fill desired and the vacuous condition in the can is then altered and a desired degree of vacuum is established by the introduction of a small and exact amount of air, such amount of air being predetermined in accordance with the amount of filling required. After the filled can is removed from the filling apparatus it is preferably introduced into a vacuum closing machine where it may be vacuumized and sealed in the usual manner.

An object of the invention is the provision of apparatus for automatically and accurately performing the steps of vacuumizing and filling cans with a liquid while protecting their walls against distortion, the control of the cans, air and liquid being such as to effect rapid and uniform filling of the can to a predetermined height without spilling and without variation.

A further object of the invention is the provision of an apparatus of the character described which automatically receives cans in untimed relation and times them with the various movements of the apparatus, positioning the cans to expose their open ends to a filling head without enclosing them into a chamber, and while under automatic valve control the cans are vacuumized, filled and discharged as uniformly liquid filled cans.

The invention also contemplates the provision of an apparatus, for vacuumizing and syruping

containers, which cannot be operated unless there is an adequate supply of syrup for filling purposes.

A further feature of the apparatus under consideration is the provision of a central valve control associated with the syrup tank which is used for separating liquid filling passages and vacuumizing passages when the apparatus is filling cans but which is also adapted for emptying of the tank of syrup after the day's run or when a change of syrup is made.

Yet another object of the invention is the provision of a no-can no-operation device in a vacuum filling machine which is associated with the filling head unit and with the vacuum filling valve and this device prevents the valve operation in the absence of a can to be filled.

The invention contemplates other mechanical features in an apparatus of simple construction wherein those parts of the machine subjected to the filling liquid may be readily dismantled and removed for the purpose of cleaning, this feature permitting rapid changing over of the machine to handle different grades or kinds of syrup and adapting the machine to small cannery uses where relatively small batch filling is necessary.

Numerous other objects and advantages of the invention will be apparent as it is better understood from the following description which, taken in connection with the accompanying drawings, discloses a preferred embodiment thereof.

Referring to the drawings:

Fig. 27 is a view similar to the upper portion of Fig. 26 illustrating the partial removal of part of one of the valve units from the filling head unit;

Fig. 28 is a sectional detail taken substantially along the line 28-28 in Fig. 27;

Figs. 29, 30 and 31 are plan sectional views taken through the valve unit and illustrating different valve settings, these sections being taken substantially in the vertical position indicated by the section line 25-25 in Fig. 23;

Figs. 32, 33 and 34 are schematic transverse sectional views of the valve showing a part of the can, the first of these views being taken substantially along the line 32-32 in Fig. 29, while Figs. 33 and 34 are taken substantially along the respective broken lines 33-33 in Fig. 30 and 34-34 in Fig. 31;

Fig. 35 is a plan sectional view similar to Fig. 29 and illustrating a different valve position;

Fig. 36 is a schematic view similar to Fig. 32 being a built-up section as viewed along the broken line 36-36 in Fig. 35;

Fig. 37 is a schematic view illustrating the valve parts in the same positions as in Fig. 32 but showing the filled can being removed;

Fig. 38 is a fragmentary joint plan and plan sectional view of the vacuum liquid trap with adjacent connections;

Fig. 39 is a transverse sectional view taken substantially along the broken line 39-39 in Fig. 38;

Fig. 40 is a plan sectional view taken substantially at an elevation indicated by the line 40-40 in Fig. 39;

Fig. 41 is a transverse sectional detail taken substantially along the line 41-41 in Fig. 39;

Fig. 42 is a transverse sectional detail taken substantially along the line 42-42 in Fig. 38; and

Fig. 43 is a plan sectional detail taken along the line 43-43 in Fig. 39.

The apparatus embodying the present invention comprises a revolving turret which carries a central liquid supply tank and a series of spaced

filling head units connected with the tank and located just outside. Can lifting units are also carried by the turret, each lifting unit being in axial alignment with and directly beneath each filling head.

Cans usually partially filled with food or other cellular contents are introduced into the machine on a pair of horizontal conveyor chains which pass them between guide rails and adjacent a timing screw. The threads of this screw engage between adjacent cans and while retarding the can travel, space and time the cans for proper feeding into the apparatus. These timed cans are then progressively engaged by a rotating can feed-in starwheel which conveys them into the turret and positions a can upon each of the can supporting units.

Rotation of the turret carries the cans on their can supporting units in a circular path of travel during which time a cam track operating through the supporting units raises each can into engagement with its associated filling head. At the time the can is being raised part of its outer wall is being engaged and guided by a half mold or fixed jaw carried on the support.

A complementary movable jaw carried by the filling head also cooperates to engage the other half of the can wall moving into place with a double jointed hinging action. These fixed and movable jaws prevent any radial movement of the can wall during a vacuumizing step of the can which follows.

A rotating valve member associated with each filling head controls vacuumizing and liquid filling of the can. This valve is set for action only when there is a can present to actuate a no-can-no-operation device. There is no valve movement of a particular valve unit during one cycle of operation if its can supply is empty.

With a can properly placed the valve associated with its unit is first actuated to establish communication between its interior and a source of vacuum. Following withdrawal of air from the can and from various passageways of the filling head, these passageways and the interior of the can are closed off from the vacuum source. The vacuumizing and the following locked vacuum period take place while the turret continues to revolve and while the can advances along its circular path of travel.

A further actuation of the valve which follows then establishes communication between the interior of the can and with a closed chamber containing air at atmospheric pressure. The exact volume of the air in this chamber has been accurately predetermined in accordance with the amount of liquid fill desired in the can and is adjustable in amount. For a given run of cans, however, each succeeding can receives the same amount of air from this chamber, the air flowing into the can expanding and reducing the degree of vacuum.

The next movement of the valve cuts off this air chamber and establishes a communication between the interior of the can and the central supply tank. The liquid in this tank is under atmospheric pressure at all times and rapidly flows into the can, seeking to fill the voids, the solids or cellular contents of the can at such time being held down by a stopper associated with the filling head.

The can and the connecting passageways in the head and valve units are thus filled and the level of the liquid in the can rises until the small amount of air in the can again compresses as a

head space until it counter-balances the atmospheric pressure on the surface of the liquid in the tank, plus the small gravity force occasioned by the higher liquid level in the tank.

5 It will be remembered that this air in the can is received in large part from the air chamber during the preceding valve movement just described and is in an expanded condition when the filling of the can begins. After such a balance 10 between the head space air in the can and the gravity and atmosphere of the liquid in the tank no further flow of syrup takes place. If a perfect vacuum in the can could be obtained and no air introduced the can would be completely filled. 15 In practice a fraction of an inch head space is desirable.

The reference to syrup and syrup filling, it will be understood, is by way of example only and is to be understood as applying equally well to 20 liquids other than syrup. By way of illustration in the filling of cans of peas, a brine is used, with tomatoes, a puree, etc., depending upon the product in the cans.

Upon the next movement of the valve the can 25 is cut off from the supply tank and the top of the now filled can is opened to atmosphere. This can is then withdrawn from the filling head by a lowering of the supporting unit and is swept from the filling machine by a discharge star-wheel.

30 The liquid within the supply tank is maintained between a maximum and a minimum level by a float device which comprises a float connected with a sliding member controlling the inner valve in a liquid tight supply line. If the 35 liquid level in the tank drops to the low position by failure of the liquid supply the float also actuates an electric stop device which stops further operation of the machine. This feature insures that there is always a sufficient supply of liquid 40 in the tank to fill the cans passing into the machine for otherwise the machine cannot be operated.

A vacuum liquid trap is associated with the machine and prevents flooding of the vacuum lines. The collected liquid may be pumped from 45 this trap back into the supply tank or to a storage reservoir. Provision is also made for draining the tank liquid into the trap. Such draining is effected by removal of the central tank valve from 50 its liquid and vacuum lines closing position. The float and connections can also be raised and removed from the tank for purposes of cleaning, etc.

This provision permits rapid changing of the 55 syrup being used and permits a draining of a light syrup, for example, from the apparatus by pumping it back to its reservoir and then substituting a heavy syrup from another batch. In some small canneries the syrup grades are sometimes 60 changed several times a day and quick changing in such cases is highly desirable.

In the majority of filling installations it is desirable that the filling apparatus be directly associated with a vacuum seaming machine and for 65 the purpose of indicating such an association a small part of a seaming mechanism is illustrated in the drawings and is herein described. Driving mechanism for the filling apparatus is preferably connected with the same driving mechanism as is 70 used on the vacuum seaming machine and will be so considered in the following description.

After a can has been filled with liquid in the 75 filling apparatus and has been swept off of its support by the discharge starwheel it is carried in a circular path of travel and then enters into

the entrance end of the seaming machine. It may be otherwise disposed of if the seaming machine is not used.

In the drawings a timing and can receiving device of a vacuum seaming machine is disclosed 5 and the following description will include that much of a seaming machine. During the transfer of the filled can from the filling apparatus into the double seamer its open end is open to atmosphere and it is only when it is received into 10 the vacuum chamber of the seaming machine that it is again vacuumized prior to being supplied with a cover and closed by the seaming apparatus.

The vacuum filling machine now being considered may be used in the capacity of a pre-vacuumizing machine and in practice it is desirable to vacuumize the can and its solid contents at a higher vacuum, about two points for example, than the vacuum used in the vacuum seaming machine and this largely prevents swelling of the 20 contents at such times since much of the air has already been withdrawn from the fruit cells and will not reenter through the syrup. This prevents overflow of the can when again vacuumized prior to final sealing. 25

General features

The revolving turret which carries the cans through the machine for vacuumizing and liquid filling or syruping comprises a tubular member 30 51 (Figs. 4 and 5) which is enlarged at its upper end in a head 52 which is formed with a cylindrical wall extending upwardly to provide a liquid supply tank 53. The tubular member 51 intermediate its length merges into a nearly flat 35 skirt 55 which spreads outwardly substantially in a horizontal plane and terminates in a vertical flange 56.

The lower end of the tubular member 51 is enlarged at 57 and encloses a ball bearing unit 40 58 which is carried upon a shouldered part 59 of a supporting column 61 positioned centrally of the turret. The column 61 is formed with a foot 62 which is mounted upon and bolted to a horizontal web 63 of a main casing 64 (see also Fig. 45 6). This casing is carried on a base 65 which extends under the filling apparatus and may also extend laterally as at 66 (Figs. 1 and 5) where it connects with a base 67 of the vacuum closing machine. The column 61 forms a stationary support for the turret member and retains it in rotating position on a vertical axis, the bearing unit 58 allowing for free rotative movement. 50

Can filling units 71 (Figs. 4, 10 and 13) are carried on the tank 53, being positioned just outside 55 of its rim and equally spaced along its periphery. Directly beneath each filling head 71 is a can support unit 72 which is carried in the skirt 55 of the turret. The cans are brought into the machine and are fed to the rotating turret being located upon a can support unit 72 and directly beneath a filling head unit 71. This feeding of the cans into the apparatus will now be described. 60

Can feeding

65

Open top cans 75 preferably containing fruit or other cellular materials and which are to be filled with syrup or other liquid are moved toward the turret by a pair of horizontally disposed, continuously moving conveyor chains 81 (Figs. 5, 15, 16) on which the cans rest. These chains 70 pass over and are carried by idler sprockets 82 mounted on a horizontal stub shaft 83 located at the entrance end of the can path. They also extend over and are propelled by similar sprock- 75

ets 84 secured to and driven by a horizontal drive shaft 86.

The shaft 83 rotates idly in a bearing 87 formed in a can feed frame 88 bolted to the side of the casing 64 and extending adjacent the turret 51. The shaft is also journaled in a similar bearing 91 formed in a side frame 92 which is mounted at its forward end on a horizontal shelf 93 projecting outwardly from the frame 88. The side frame 92 is tied to the frame 88 at its outer or rear end by a tie plate 94.

The upper run of one chain 81 is guided in a horizontal groove 95 (Figs. 13 and 16) formed in a grooved plate 96 bolted to the side of a block 97 carried by the frame 88 where it extends between the sprockets 82, 84. In a similar manner the upper run of the other chain is carried in a horizontal groove 98 formed in a grooved plate 99 carried in a longitudinal slot 101 formed in the frame 92, being bolted thereto. This plate 99 is located directly opposite to the plate 96 and the two plates provide the proper guiding supports for the conveyor chains.

The shaft 86 rotates in bearings 108, 109 (Fig. 15) formed respectively in the frames 88, 92 and carries a gear 111 which is secured to its outer end and which is located in a gear box section 112 of the frame 92. This gear 111 meshes with a similar gear 113 (Figs. 13 and 15) carried on the outer end of a horizontal shaft 114, the shafts 86, 114 being parallel and in the same horizontal plane. A gear box cover 115 is secured to the gear box 112 and protects the gears 111, 113.

The shaft 114 is journaled in bearings 118, 119 located adjacent the bearings 108, 109 and like the latter are formed in the frame parts 88, 92. This shaft extends across and between the upper and lower runs of the chains 81. Its inner end carries a bevel pinion 125 which meshes with a gear 126 keyed to a vertical shaft 127 journaled for rotation in bearings 128 formed in the frame 88.

The lower end of the shaft 127 carries a gear 131 (Fig. 6) which meshes with and receives rotation from a gear 132. The frame 88 is formed with a pocket 133 and the gears 125, 126 are located in this pocket. A table plate 134 rests upon and forms a top for the frame 88. This plate also provides a cover for the gear pocket. The frame wall is also enlarged in a bulged section 135 which provides a housing for the gear 131.

The gear 132 is the main driving gear for the turret unit and is keyed to the lower end of the turret section 57 (see Fig. 4). Gear 132, together with the turret and all parts carried thereby is driven through connection with a gear 141 (Figs. 4, 6 and 9) which is carried on the lower end of a vertical shaft 142 journaled in bearings 143 formed in a housing frame 144 bolted to one side of the casing 64. The frame 144 is bulged outwardly at 145 to provide a housing for the gear 141.

The gear 141 is driven by connection with teeth 146 formed on a double gear 147 mounted upon 65 and freely rotatable on a supporting stud 148 carried in a lateral housing section 149 of the frame 144. A cover member 151 is bolted on the frame part 149 and assists in holding the stud 148 in position as well as providing easy access thereto when the cover is removed.

The double gear 147 also has bevel gear teeth 155 which mesh with a tubular gear 156 keyed to a horizontal drive shaft 157. A tubular section 158 of the gear 156 is journaled for rotation 75 within a bearing 159 formed in an auxiliary frame

member 161 bolted to the frame part 149. This tubular gear part 158 is threaded to receive lock nuts 162 which are located outside of the bearing 159 and which hold the gear in rotatable position. A cap 163 is bolted to the frame part 161 and protects the end of the gear and the lock nuts.

Drive shaft 157 may be any suitable driving part and is here shown as extending from the general direction of the double seaming machine 10 associated with the filling apparatus. Preferably this drive shaft is a major driving element of the double seaming machine and when so formed insures synchronism of operation between the filling apparatus and the double seamer. 15

Can timing

The cans 75 being brought into the apparatus by the conveyor chains 81 are guided in a straight path of travel by various guide bars or rails. 20 The first of these comprises a side rail 165 (Figs. 5 and 16) bolted to and resting upon the horizontal or top part of the side frame 92. On the opposite side a movable side guide rail 166 is disposed, being mounted on the table 134 (see 25 also Fig. 21).

This rail 166 adjacent its two ends is formed with rearward extensions 167 which rest on top of a support block 168. The block 168 is mounted on the table 134, a foot 169 of the block 30 being slotted at 171 for the reception of a clamping bolt 172 screwed into the table 134. This construction permits adjustment of the block relative to the table.

The rail 166 is adapted to be engaged by an incoming can on the chains 81 and assists in placing the can in proper position in a timing member. In this positioning of the can for timing the can sometimes crowds against the rail and pushes it back toward the block 168. This movement is made possible by bolt and slot connections between rail and block. 40

The latter is formed with a forward projection 173 which extends beneath the rail extensions 167 and is slotted at 174. A bolt 175 extends 45 through each slot and holds the extensions 167 against the block 168 and the rail 166 down on the table 134 while permitting its movement. Springs 176 are interposed between block and rail and tend to force the latter back and the 50 cans over and into the timing member.

This timing member comprises a timing screw 178 which is provided with an encircling thread 179. This thread, adjacent the entrance end of the can travel, is relatively narrow on the face 55 of the thread and increases in face width toward the opposite end. At the same time the diameter of the thread 179 increases.

Screw 178 is continually rotated and as the cans in untimed processional order move adjacent the screw and come into the influence of its thread, their travel is retarded. The increased spacing of the thread on the timing screw thus operates to space the cans and to correctly time them for proper feeding to the turret. 60

The timing screw 178 (Fig. 16) is formed with a short shaft part 185 and a long shaft section 186. Shaft 185 is journaled in a bearing 187 formed in a bracket 188 mounted upon the frame 92 and the long shaft section is journaled in a 70 bearing 191 formed in the frame part 92. This frame part at this position also provides a bearing 192 for a horizontal shaft 193 which is parallel to the shaft 186.

These two shafts are driven in synchronism by 75

5 a gear connection formed with a pinion 194 keyed to shaft 196 and a gear 195 carried upon the other shaft. These gears are contained within a pocket formed in the frame 92. A cover plate 196 secured to the frame closes the pocket. The shaft 193 carries a spiral pinion 197 (Figs. 13 and 16) which meshes with a spiral gear 198 carried on the drive shaft 114 (Fig. 15).

10 As the can 76 under control of the thread 178 of the timing member approaches the discharge end it is brought into a pocket 201 of a transfer starwheel 202. A guide rail 203 is carried by the frame 88 and forms a continuation of the guide member 166 and the former holds the can in the 15 screw until it enters the starwheel pocket. The guide rail 203 is cut away at 204 to allow for clearance of the starwheel. A shell section 205 carried on the frame 92 partially covers and protects the timing screw.

20 As soon as the can is engaged within a pocket 25 of the starwheel it moves adjacent an outer circular guide rail 206 bolted to the table 134 and this rail retains the can within the starwheel pocket while the latter carries it toward a can support unit 72 of the turret. The starwheel 202 is mounted upon the upper end of the shaft 127 and is rotated therewith.

This shaft is formed with a shoulder 211 on which the gear 126 rests (Fig. 13) and this gear 30 is provided with a tubular part 212 which provides a spacer as well as a support for the starwheel. A bolt 213 and a washer 214 clamp the starwheel rigidly against the gear part 212 and hold it on its shaft.

35 *Can support unit*

Each can support unit (Figs. 5, 12 and 13) comprises a platform 225 on which the can is positioned by the starwheel 202. This platform 40 is provided with a depending tubular body 226 and is mounted upon a plunger 227 which slides within a tubular housing 228 mounted upon the skirt portion 55 of the turret. Plunger 227 carries a cam roller 229 rotatably mounted on a horizontal pin 231 which is held in fixed position within the plunger. An auxiliary roller 232 is also rotatably mounted on the pin 231.

As the turret parts rotate and a platform 225 is brought adjacent the starwheel 202 the can 50 76 is slid into position on top of the platform. This is done without interruption of the rotation of the turret or the advancement of the support unit. At all times the cam roller 229 is riding on a circular cam track 234 which is formed in a ring cam 235 bolted upon a second web section 236 (see also Fig. 4) formed as an integral part of and located above the web 63 of the casing 64.

After receiving its can, the can support unit is raised by lifting of its roller 229 as it passes along 60 an upwardly inclined section of the cam track 234 and its superimposed can is thus lifted into its associated filling head unit 71 directly above. The inner edge of the ring cam 235 along one side extends upwardly and inwardly into an 65 overhanging arcuate cam track section 237 which engages above the roller 232 during a part of the travel of the support unit and insures a lowering of the platform 225 and can when desired.

70 *Filling head unit*

The filling head unit 71 comprises a body 241 (Figs. 13, 23, 24, 26 and 28) which is formed with a reduced neck 242 merging into a vertically extending right angled foot 243 by means of which 75 it is adjustably secured to and carried on the

outside wall of the tank 53. The lower part of the outside tank wall is vertically slotted at 244, there being a number of these slots equally spaced around the outside of the tank.

Each foot 243 is held within a slot 244 being 5 clamped on each side by clamping blocks 245. Each block is located between two of the filling head bodies and is adapted to engage adjacent sides of adjacent bodies 241 as best illustrated in Figs. 24 and 28. Each foot 243 is vertically 10 grooved along its side edges as at 246 and the lower part of each clamping block extends into two adjacent slots 244.

Each block 245 is formed with an upper projection 247 and lower projections 248 and is 15 mounted on a stud 249 threadedly secured in the tank wall between two adjacent slots 244. When in clamped position the projection 247 of each block rests against the outer wall of the tank at a point above the filling head body and 20 its lower projections 248 engage within the slots 246 of the walls 243 of adjacent filling head units. A nut 251 threadedly secured on the outer end of each stud 249 holds its block 245 in clamped position. To assist in closely adjusting the body 25 241 so that it can be clamped in the desired position as just described, an adjusting bolt is used as will be hereinafter described.

Each unit body 241 (Figs. 13 and 26) carries a 30 rubber ring 252 which is vulcanized or otherwise secured on the outside of a holding ring 253. The holding ring is formed with an annular internal shoulder 254 which is engaged by a top- 35 per block 255 located inside of the ring. A screw 256 extends through the center of the topper member and is threadedly secured in the bottom of the unit body. This construction securely holds the parts 252, 253, 255 as a single unit.

The rubber ring 252 may be formed with an inclined lower edge adapted to be engaged by the upper open end of the can 76 when it is raised into position with the can support unit 72. The 40 resiliency of the ring effects a tight seal for the open end of the can which is then in position for vacuumizing and filling.

Where a product such as peaches or other 45 large fruit is being handled the lower surface of the topper 255 is hollowed out as at 257 to permit the solid contents of the can to extend up into the topper without injury to the fruit, the 50 topper at the same time holding the fruit.

55 *Can wall protecting jaws*

It is contemplated that a high vacuum will 55 usually be desired in the liquid filling of a can 15 while clamped in the filling head and in order to prevent collapse or distortion of the can wall by the excessive atmospheric pressure on the outside, can encircling and protecting instrumentalities are provided. These clamp against 60 the walls of the can and by preventing their movement during the vacuumizing operation prevent distortion or collapse.

For this purpose a fixed jaw 261 (Figs. 13 and 65 26) is carried by the platform 225, being secured to an upward extension 262 by a bolt 263. The inner wall of this jaw corresponds in size and curvature with the exterior wall of the can body and is substantially a half cylinder so that a substantial section of the can body is engaged 70 by the jaw.

A movable jaw 265 (Figs. 13, 23 and 26) is provided for encircling the opposite half portion of the can wall. The jaw 265 is secured by bolts 75 266 to a holding member 267 which is provided

with spaced arms 268 (see also Fig. 22) which are pivotally mounted on a pin 269 carried in and extending beyond opposite sides of the body part 241. The movable jaw can be hinged on the pin 269 through practically 135° of movement. A cam, or more accurately two cams, control this movement.

- The arms 268 are enlarged at 275 to provide bearings for a horizontal pin 276 which carries 10 a cam roller plate 277. This plate is spread out into a pair of bosses 278 which encircle the pin 276, a set screw 279 carried by one of them holding the plate and pin together. The plate carries a shouldered and headed stud 280 15 which is held by a lock nut 281. The stud 280 carries a cam roller 282 which is acted upon by the pair of cam tracks previously mentioned to swing the jaw frame 267 one way or the other on its pivot 269.
- 20 One of these cam tracks is engaged by the roller 282 when the jaw 265 is to be lifted and the other cam track is engaged by the same roller during the time the jaw is brought into its protecting engagement with the wall of the can body. The engaged position is illustrated 25 in Fig. 26.

The horizontal pin 276 rocking in the bearings 275 allows for a slight movement between the frame part 267 and the cam roller mounting 277 and provides for a yielding clamping 30 action of the jaw 265 on the wall of the can as it is held in the filling head. Stop lugs 283 (Figs. 22 and 26) formed as integral parts of the bosses 278 project above the jaw frame 267 and limit 35 the movement of the cam roller plate 277 in one direction.

The plate 277 is provided with a bore 285 in which a spring barrel 286 is slidably mounted. A spring 287 located in the spring barrel normally tends to push the latter outwardly against 40 the jaw 265 to hold the cam roller 282 against one of the cam surfaces now to be described.

The first of the cam members for the movable jaw 265 comprises a ring segment 291 (Figs. 45 45 and 26) which extends for more than half a circle having an inner circular cam wall 292 which is concentric to the center of the supply 50 tank 53. This ring segment is stationary, being supported at three spaced positions around the center of the supply tank.

The middle of these supports comprises a vertical pipe 293 (Figs. 4, 5 and 10) which is held 55 in a split bracket 294 clamped in fixed position by bolts 295 extending across the split. This bracket is formed with connecting webs 296 which are bolted to a vertical wall of the casting 64.

The cam segment 291 is provided with a lug 297 which is bolted to a split clamp sleeve 298 60 securely held in an adjusted vertical position upon the pipe 293. The cam segment is also provided with two lugs 299 (Figs. 7 and 10) each of which rests upon and is bolted to a cap member 300 secured to the upper end of a pipe 301. 65 The two pipes 301 are held in suitable brackets similar in design to the bracket 294 which are also bolted on the casing 64.

The movable jaw 265 when brought into the can clamping position shown in Fig. 26 is held 70 against the can wall by engagement of the roller 282 with the cam face 292 of the cam segment 291. It remains in clamped position throughout the extent of the cam segment.

When the roller 282 passes the end of the 75 cam segment it comes under the influence of

the second of the cam members referred to which is a lifting cam 302 of peculiar shape as best shown in plan in Fig. 10. It is also only a segment of a circle and its ends are bolted to the ends of the cam segment 291 and its center part is bolted down on and carried by a pipe 303 (Fig. 5) clamped in the housing 144. These cam members 291, 302 together complete the circle which surrounds the turret, the supply tank and the filling heads.

The cam member 302 is provided with a cam groove (Figs. 4 and 13) along which the roller 282 passes and between the walls of which the roller is confined during its travel along the cam groove. This cam groove picks up the roller 15 from the position shown in Fig. 26 as it leaves the cam surface 292 and pivoting the frame part 267 on its connection 269 brings the jaw 265 in the open position illustrated on the right hand side of Fig. 4 which is the extreme lift of the 20 jaw.

With the jaw so lifted, a filled can in the filling head is ready for discharge. Just after a succeeding can has been located within the filling head, the roller 282 passes along the end 25 of the cam groove and is again brought along side of and in engagement with the cam track 292. This movement of the clamping jaw 265 and the cooperating movement of the can will be hereinafter fully described.

The cam 291 and a portion of the cam 302 are partially enclosed by an inverted bowl shaped shell 304 (Figs. 1, 4, 10 and 13) which extends around a substantial part of the upper portion of the apparatus nearly enclosing the filling 30 heads. The shell 304 is supported upon three spaced brackets 305 (shown in detail in Fig. 7) and a fourth bracket 306 (shown in detail in Fig. 8). The brackets 305 are mounted upon and bolted to the cam segment 291. The bracket 40 306 is mounted upon one end of the cam member 302.

The shell 304 is secured by bolts 307 to the outer wall of the brackets 305 and is similarly secured by a bolt 308 to the bracket 306. The 45 upper part of the shell is cut away at 309 to allow clearance around the respective brackets 305, 306. The spaced ends of the shell 304 are bolted at 310 to suitable bosses formed in the outer wall of the cam member 302.

Valve unit

With the can 75 securely clamped within the filling head 71 and its upper edge engaging the can rubber 252 the can is ready for the first or 55 vacuumizing step. To control this vacuum step and also succeeding filling steps a valve unit is utilized for each filling head. Each valve unit is carried in a bracket 315 (Figs. 22 and 26) which is provided with a foot 316 located in a 60 vertical groove 317 formed in the tank wall 53 directly above as a part of the filling head body groove 244.

The provision for the fine adjustment of the vertical position of the filling head unit 241 in 65 relation to its associated valve unit can now be considered. A vertical adjusting bolt 318 is located within the foot 316 of each bracket 315. The bolt 318 is threadedly connected at 319 with the bracket 315 and is formed with a head 320 70 which rests in a slot 321 (Figs. 26 and 28) formed in the filling head body 241. The upper end of the bolt 318 extends above the bracket 315 and carries a nut 322 which is pinned on the bolt. This nut provides means for turning 75

the bolt to raise and lower the filling head body during its adjustment as has already been described.

Each valve bracket is held in position on the tank by clamps 324 (Figs. 22 and 23), there being a clamp on each side of each valve foot 316. Like the clamping blocks 245 for the head bodies, each clamp 324 holds two adjacent brackets 315 for the valve units.

10 Each clamp 324 is held in its clamped position by a lock nut 325 threadedly engaging the outer end of a stud 326 threaded into the tank wall. This arrangement, while firmly holding the bracket in adjusted position, allows for easy assembly or removal as desired, it being only necessary to loosen or remove the lock nuts 325 for this purpose. A dowel pin 321 may also be used to designate the exact vertical position for the bracket, each dowel pin passing through the foot 316 and 15 extending into the wall of the tank 53.

Each bracket 315 supports the actuation or control for a rotary valve 331 (Figs. 23, 25 and 26). The valve 331 is formed with a smooth bottom surface 332 which engages a smooth surface 333 (see also Fig. 24) formed on the top of the body member 241. The engaged surfaces 332, 333 are so closely fitted that they provide an airtight and liquid tight joint which is maintained during rotation of the valve 331 on the body.

30 It is rotation of this valve 331 which regulates the various operations incident to the vacuumizing and filling actions of the apparatus. The valve is constructed so that it can be slid out of its assembled position and can be removed from 35 the filling head for purposes of cleaning or otherwise.

The valve 331 in its assembled position (Fig. 23) is held down in airtight engagement against the body 241 of the filling head by clamping blocks 335 (Figs. 22, 23 and 27) but this does not prevent free turning of the valve on its seat. A top overhanging section 336 of each block rests on top of and within an annular groove 337 cut in the valve. Screws 338 threadedly engage the body 241 (Fig. 24) and hold the blocks in position.

40 An intermediate position in the removal of the valve 331 from the head is shown in Fig. 27. The valve has a stem 341 which is slotted at 342 and a tongue 343 formed on the lower end of a vertically extending sleeve 344 is adapted to engage within the slot. With tongue and slot positioned along a radial line of the tank 53, the valve may be slid out or in and when in the assembled position the tongue and slot connection insures 45 operative movement of the valve and sleeve.

50 Sleeve 344 is rotatably mounted in the bracket 315 and extends upwardly to a point above the bracket. The upper end of the sleeve passes through a valve locking block 345 (Figs. 3, 23, 26 and 27) and thence through a four-fingered spider 346. Block 345 and spider 346 are keyed to the sleeve 344 and a lock nut 347 threadedly engaging the upper end of the sleeve holds these parts together as a unit and in rotatable position 55 within the bracket.

The spider 346 is the valve turning part of the valve unit and is successively engaged by four actuating devices positioned along the path of travel of the valve unit as the filling heads, tank 70 and other associated parts of the machine move with the rotating turret 51. The first of these actuating devices acts to set the valve for the other three actuating elements only when a can is presented for filling. This setting device will now be 75 described.

No-can-no-valve movement

If there is failure of feeding of a can to a can support unit 72 no valve movement of the associated valve will take place during one complete revolution of that particular filling head with the revolving turret. In other words, when there is no can to be filled no vacuum is applied to the filling head and no syrup is discharged through the head. This does not in any way affect any of the other heads and the machine therefore acts entirely automatically to fill such cans as are in proper position to be filled.

10 An actuating lever 355 (Fig. 5) is disposed in the path of travel of a can clamped in a filling head 71 by its associated can support unit 72. The position of this lever is such as to be engaged by a can as soon as it has been positioned within the filling head which is just after it has been released from the starwheel 202. Upon engagement by a can the lever 355 is moved outwardly or away from the center of the turret.

15 Lever 355 is mounted upon the lower end of a vertical rod 356 (Figs. 1, 5 and 20) which is mounted in a bearing sleeve 357 resting upon and bolted to the cam segment 291. The upper 20 end of the shaft 356 carries an arm 358 which extends in front of the lower ball shaped end 359 (Fig. 8) of a bell crank lever 361 mounted for oscillation on a pin 362 carried in the upper end of the bracket 306. This bracket is slotted at 363 25 for the bell crank lever and a spring barrel 364 backed up by a spring 365 slides within a horizontal bore 366 formed in the bracket 306.

30 The spring barrel 364 under the action of its spring rests against the rear end of the ball 359 35 of the bell crank lever and moves it against the arm 358, this position being illustrated in Fig. 8. When in such position, a finger 367 of the bell crank lever is held above the path of travel of the spider block 346 of the valve control. Accordingly, as the unit passes this point the valve spider remains in the position as illustrated and it continues its travel in such position.

35 When a can engages the lever 355 and oscillates the shaft 356 the arm 358 pushes back the 40 ball end 359 of the bell crank lever against the action of the spring 365 and oscillates the bell crank lever to bring its finger 367 down into the 45 position indicated by the broken line in Fig. 8 where it is in the path of travel of a finger 371 50 (Figs. 8, 22 and 26) which projects outwardly from the body of the spider 346. As the filling head passes the bracket 306 this finger 371 engages the finger 367 of the bell crank lever and the spider 346 is moved through an angle of 90° as 55 the head continues on past the finger.

This movement of the spider 346 effects the first valve movement which causes the interior of the can to be placed under vacuum as is about to be described in detail. In the event that the finger 371 of the valve spider is not engaged at this point then the filling head unit with the valve will be carried throughout its entire movement with the revolving turret without any valve action.

60 The bearing sleeve 357 (Figs. 1 and 20) carries a lug 372 which projects upwardly alongside of the arm 358 and a stop screw 373 is threadedly secured in the lug. The arm 358 is formed with a projection 374 which strikes against the screw 70 65 373 and limits the inward movement of the arm and, through the rod 356, the inward position of the lever 355.

75 Provision is made for preventing inadvertent or mistimed movement of the valve and this is

done by locking the valve and valve spider through the medium of the block 345. This block, as shown in detail in Figs. 2 and 3, is of general cylindrical shape and has pointed projections upon three different levels.

5 The lowermost projection is formed as a section 375 having a forward corner 376 and a rear corner 377. The vertical face of the projection is curved to correspond in shape to the inner wall of a lower 10 locking ring 378 (Figs. 1, 7, 8 and 13) which rests upon and is carried by the brackets 305, being positioned in a groove 381 formed in the upper top part of each bracket.

Ring 378 supports a middle ring 382 which is of 15 the same inner diameter and which also acts to hold the valve in position after it has been actuated by engagement of its finger 371 as just described. The ring 382 is grooved at 383 and an upper ring 384 is located upon it.

20 The three rings 378, 382, 384 are clamped in position upon each of the brackets 305 by a clamping block 385 having a pair of feet, one of which rests upon the upper top ring 384 and the other upon a projection 386 formed in the top of the 25 bracket. A bolt 387 threadedly secured in each bracket locks the clamping block in fixed position. This construction, while holding the rings in fixed position, permits easy shifting of the rings relative to each other for a purpose hereinafter 30 fully described.

As the valve unit of a particular filling head comes adjacent the bracket 305 (indicated as a station A Fig. 1) its finger 371 will either pass under the raised finger 367 of the bell crank lever 361, this being when there is no can present in 35 the filling head, or will be engaged by the bell crank finger. In either event the holding action on the valve is released. This is accomplished by relieving the inner wall of the ring 378.

40 For this purpose the ring 378 is cut away in a notch 391 (Fig. 2) which permits entry of the point 376 of the block 345 in the event that the valve finger 371 is engaged. A valve movement then takes place, as is shown in Fig. 2, the projection 376 passing freely into the notch and the 45 valve 331, sleeve 344 and block 345 turning the necessary amount.

This movement then presents a curved surface 392 of the block to the inner wall of not only the 50 lower ring 378 but also to the inner wall of the upper ring 384. The valve unit is now locked in its actuated position against further forward rotation by sliding engagement of the surface of a point 393 on the block 345, which forms part of the curved surface 392, against the upper ring 384.

55 No backward rotation can take place by reason of the sliding engagement between the curved surface 392 alongside of the projection 376 and the wall of the lower ring 378. The locking block 60 345 is thus held against turning in either direction until the next valve operating position is reached. This will be fully described following the description of the first valve movement or setting for the vacuum step at the station A.

65 Vacuumizing the can

Each filling head body 241 as best illustrated in Figs. 24 and 26 is formed with a vertical passageway 401 which connects with an inclined passageway 402. This latter opening communicates with an inclined passageway 403 (Figs. 4, 11 and 26) formed in the head 52 of the turret 50. The passageways 403 extend radially and below the bottom of the tank 53, there being a passageway 75 for each filling head. The inner and lower tank

end of each passageway 403 terminates in the side wall of a chamber 404 which is formed in the turret head, the top of the chamber being closed by a disc valve 405 which normally rests within a depression 406 formed in the bottom of 5 the tank.

The valve 405 besides enclosing chamber 404 also forms a bottom closure for the tank and to provide a liquid seal, carries an annular gasket 407 embedded in a groove 408 formed in its under 10 surface. As long as the valve closes the tank bottom liquid cannot flow into the chamber 404 and this chamber is utilized as a vacuum chamber and is used in vacuumizing the can.

The valve 405 (Figs. 4 and 11) is provided with 15 a hollow stem 411 which extends downwardly through an opening 412 formed in the center of a web 413 closing off the upper part of the column 51. The stem 411 is cut across with openings 414 forming passages between the chamber 404 20 and the interior of the stem.

A pipe 421 is located centrally of the turret and is supported from above by a threaded collar 422 which is seated upon a gasket 423 and bolted to the under surface of the web 413. The lower end 25 of the pipe projects through a collar 424, which is formed with a lower skirt surrounding a stuffing box 425. Pipe 421 is connected with the upper end of a pipe elbow 426, the latter being provided with an attaching flange 427 which is 30 secured to the wall 63 of the casing 64.

A horizontal arm 431 of the elbow 426 (Figs. 4, 38 and 41) is formed with a flange 432 which connects with a flange 433 projecting outwardly from the casing of a vacuum liquid trap 434. The 35 interior of the elbow 426 communicates with the interior of an inner tubular member 435 formed as a part and near the bottom of the vacuum trap. This member 435 is open at one end and a domed plate 436 bolted on the casing provides a 40 connecting passage between the bend of 436 and the interior of the trap. The interior of the tubular member 435 also communicates with the interior of a vertically extending tubular section 437 (see also Fig. 39) projecting upwardly into 45 the interior of the trap.

The vacuum trap 434 rests upon the base 65 and is formed with a foot 438 for this purpose. It is also bolted along one side to the vertical wall of the casing 64. For its side connection the trap 50 is formed with a laterally extending curved wall 441 which is bolted at its ends to the wall of the casing and this closes off an opening 442 in the casing wall.

A horizontal wall section 444 (Figs. 39 and 41) 55 forms the top of the vacuum trap 434 and an opening 445 in the wall is closed by a flanged cover plate 446 bolted in closing position. The cover 446 is formed in its center with a depending annular skirt 447 which extends down through 60 the opening 445 and surrounds the upper end of the pipe member 436, the inside of the skirt being considerably larger in diameter.

The interior of the vacuum trap 434 is adapted to be vacuumized at all times during the operation of the machine and for this purpose there is provided a pipe 451 (Figs. 39 and 42) which is connected with a collar 452 to the top wall 444. This pipe 451 may connect with any suitable source of vacuum such as a vacuum pump or 70 vacuum tank.

As the air is removed from the interior of the vacuum trap 434 through the pipe 451 air is also extracted from the interior of the pipe sections 437, 435 formed in the tank and from the elbow 75

426 and pipe 421 and also from the chamber 404 by way of the openings 414 in the central valve stem. The air is accordingly withdrawn from the passages 403, 402 and 401 in the filling heads.

5 To prevent the passage of any liquid into the vacuum lines which is drawn in as far as the pipe 437 a deflecting member is used at the entrance to the interior of the collar 452. This member comprises a conical plate 455 (Fig. 42) which is located in inverted position beneath the mouth of the collar and just below the top wall 444 of the liquid trap. This conical plate is an integral part of an outer plate 456 and extends through an opening 457 formed in one wall of 10 the tank 434, the plate 456 being bolted to the tank as best shown in Figs. 38 and 42.

Passages other than the passageways 401, 402 are also formed in the filling head body 241 and it is the mission of the valve 331 to connect certain of these passageways. The different positions of the valve are effected by turning on its vertical axis and such positions provide for the proper selection of such of these connections as are desired to produce a given result. This will 15 now be further explained in detail.

An oblong chamber 459 (Figs. 25 and 26) is formed in the lower part of the valve 331 and one end of this opening is at the center of the valve and is therefore at all times in communication with the upper end of the passageway 401 and is exhausted of air at all times. When a can 75 is first raised into a filling head the valve 331 and the filling head body 241 are positioned as shown in Figs. 29 and 32, the passageway 401 20 being the only connection with chamber 459 and the pull of vacuum in the filling head is therefore against a dead space, i. e., the chamber. At the same time passageways in both the valve and the filling head body are open to atmosphere.

40 The filling head body 241 is cut through with a nearly vertical passageway 461 (Figs. 24 and 32) and its lower end connects with inner and outer inclined ports 462, 463 passing through the top- 45 per. Port 462 leads toward the center of the topper and port 463 terminates just inside of the ring 253. When the can 75 is clamped against the rubber 252 its open mouth is below the ends of their ports.

In this same position the upper end of passageway 461 communicates with the lower end of a 50 vent opening 464 which extends upwardly through the valve 331 and is open to atmosphere.

The upper end of passageway 461 also communicates with an inclined port 465 cut in the 55 valve and this port connects with a central chamber 466 (Figs. 26 and 32) formed in the upper end of the valve. The chamber 466 is in communication with the lower end of a tube 467 which extends upwardly through the sleeve 344. 60 This tube is part of a vacuum filling control unit used to regulate the height of fill in the can as will be hereinafter fully explained.

The tube 467 is inserted from above and its lower end, where it passes into the stem 341 of the valve 331, is sealed against air leakage by a packing 468 which surrounds its bottom end and which is located in a counter sink formed in the valve stem. The tube permits free rotation of the valve by the sleeve 344 and the spider 346 70 as previously described, but prevents accidental removal of the valve from the filling head. To effect such removal, however, it is only necessary to lift the tube so that its lower end is above the bottom of the sleeve as is shown in Fig. 27.

75 An air cylinder 469 (Fig. 26) of the vacuum

filling control unit is threadedly secured to the upper end of the tube 467, this being above the upper end of the sleeve 344. A lock nut 471 also threaded on the sleeve locks the cylinder in place. A threaded cap 472 closes the top of the cylinder. Displacement blocks 473 are placed loosely inside of the cylinder and are used to block off some of its interior area, this being a feature of the vacuum filling control previously mentioned.

When the can 75 comes into the filling position 10 with the valve positioned as in Figs. 29 and 32 the interior of the can is open to atmosphere through the ports and passageways 463, 462, 461, 464 and the interior of the cylinder 469 and the interior of the tube 467 is also open to atmosphere through the ports and passageways 464, 15 461, 466 and through the tube 467.

An inclined port 474 is also located in the valve 331 its upper end connecting into the chamber 466 opposite to the end of the port 465. The lower 20 end of the port 474 is blocked off in this first or neutral valve position by the filling head body 241. It is later utilized in controlling the vacuum fill level as will be fully explained in the proper place.

25 The lower surface of the valve cooperates sufficiently close with the upper surface of the filling head body to prevent any substantial leakage of air therebetween but a further liquid seal is made for the valve, the liquid indirectly maintaining 30 better working conditions as well as directly sealing. An annular groove 475 (Figs. 24 and 32) is formed in the upper surface of the part 241 directly beneath the outer rim of the valve 331 and this groove is filled with a liquid such as water. 35 This water is supplied in any suitable manner, only a few drops being necessary for each cycle of movement of the machine.

The liquid is drawn in from time to time between the valve surfaces and advantage is taken 40 of this fact to maintain a better valve seat. Such liquid acts as a solvent to syrup spreading outwardly between the valve surfaces and prevents crystallization of sugars in the syrup. Such syrup crystals being hard act as wedges and keep 45 the valve surfaces apart and interfere with the efficient seating of the valve and best results are obtained where the syrup never crystallizes. The water thus acts in a double role for maintaining a 50 relatively tight fit.

Both the head body 241 and the valve 331 in the plan views (Figs. 29, 30, 31 and 35) are provided with arrows marked *o* which indicate a point of reference on each and by referring to the 55 relative positions of the head and valve arrows the angular valve movement, in a counter-clockwise direction, may be easily noted. For example, the neutral valve position with parts under atmosphere which has just been described and as shown in Fig. 29, is indicated by the arrows *o* in alignment.

At station A (Fig. 1) following the first valve movement the arrows *o* (Fig. 30) show a partial turn through 90° the valve having moved from the position indicated in Figs. 29 and 32 into that 65 shown in Figs. 30 and 33. This is the vacuumizing step and air from inside the can now passes out through the openings 463, 462, 461, 459, 401 and 402 and thence into the vacuum trap 434 and connecting pipes, etc., as previously described. 70 This quadrant turn of the valve, it will be observed, positions the chamber 459 so that it bridges the passages 401 and 461.

In addition to this vacuumizing of the can, air or syrup is also withdrawn from a chamber 461 75

formed in the valve. This is shown in Fig. 33 where it will be observed that the top end of the passageway 461 is grooved out along one edge at 482 to connect with the inner edge of the chamber 481. This chamber is formed with arcuate side walls and in running through the first can only air fills the space which is drawn off at this time.

After that, however, the chamber remains practically filled with syrup and a relatively small portion is drawn into the vacuum lines at the vacuumizing of the next can and this continues for each can following. This small amount of liquid is utilized to prevent crystallization (where syrup is used) in the small passageways. Crystallization in these passageways is caused by extracting moisture from the sugar in the syrup which has a tendency to hang on the passageways 461, 462 and 463 and is most apt to occur in the passageways which are used for vacuum as the moisture in the syrup is drawn away in the air flow. By circulating even the relatively small quantity of liquid through these passageways following each vacuum step, as just described, this condition is avoided. In this manner crystallization is entirely prevented in the passageways, chamber and openings 403, 402, 401, 459, 461 and 463 as well as in the port 462.

It will be observed that the upper surface of 30 the filling head body 241, in this vacuum valve position, blocks off the lower ends of the ports 464, 465 and 474 in the valve 331 and the atmospheric air in both the cylinder 469 and tube 461 is locked in. The can is thus vacuumized to the 35 maximum degree available in the system. On the next or second movement of the valve, this vacuum in the can is blocked off from the vacuum source and then the interior of the can is brought into communication with the interior of the cylinder for the adjustment of the vacuum necessary to obtain the desired filling height. This takes place in the following manner.

Adjusting the vacuum to the desired fill

45 The second movement of the valve is also through 90° of turn or from the position of Figs. 30 and 33 into that of Figs. 31 and 34. The valve movement takes place at station B (Fig. 1). At this station the top ring 384 is cut away to provide 50 a notch 505 which, like notch 391 at station A, allows for clearance of the block 345 when the valve is moved through its second quadrant of turn.

The spider 346 is formed with a second finger 55 506 (Figs. 1, 22 and 23) which is just forward of the finger 371 but at a lower level. This finger is engaged by an actuating finger 507 which extends within the path of the finger 506 and which is bolted to the top ring 384 adjacent the notch 60 505. It will be observed that the arrow o (Fig. 31) of the valve 331 is now directly opposite or on the other side of the arrow of the filling head, the valve having moved through 180° in its two movements.

65 As the top point 393 of the locking block 345 clears through the notch 505 of the ring 384 a third side 508 of the block (Figs. 2 and 3) is presented to the locking rings 382 and 384. During the travel of the valve from station B until it is 70 again moved at an adjacent station C (Fig. 1), the side of the point 393 passing along the upper ring 384 prevents inadvertent forward valve turning and an intermediate point 509 extending outwardly from the body of the block 345 on the 75 side 508 passes along the intermediate ring 382

and prevents inadvertent valve turning in the other direction.

It is with the valve in the position of Figs. 31 and 34 that the control for height of liquid fill in the can takes place. Such control depends on 5 the principle that any air in a can must be displaced by an inflowing liquid before the latter will enter the can.

The exact amount of atmospheric air in the cylinder 469 and tube 467 has been carefully determined and this amount is adjustable since the cylinder if filled to capacity with the displacement blocks 473 will contain only a minimum amount of air and if empty the maximum. Between these limits any desired air capacity can 15 be had.

The vacuumized interior of the can, with this valve setting, is in communication with this measured quantity of air which passes freely from chamber 466 by way of the port 474 and 20 passage 461 with which it now connects. From passageway 461 the air thence passes through the passageways 462, 463 and thence into the can. In other words, the air expands to fill all of the communicating spaces and the degree of 25 vacuum in the can is reduced from its maximum to its filling vacuum. The space in the can to be filled with liquid being substantially the same for each can and the degree of vacuum being also uniform the height of fill is therefore predetermined.

While this changing of the atmosphere within the can and filling head is taking place liquid from the filling tank 53 is coming into position ready for filling into the can at the third valve 35 movement. When the valve 331 is in the position shown in Figs. 31, 34 the forward end of the chamber 481 comes into communication with the end of a passageway 515 cut in the body 241 adjacent the tank. The other end of passageway 40 515 communicates with a radial passageway 516 (Figs. 4 and 11).

Each passageway 516, like the passageways 403, are formed in the bottom of the tank 53, there being a passageway for each filling head. 45 The inner or tank ends of the passageways 516 terminate in the wall surrounding the depression 406 in the tank and provide conduits for the liquid in the tank. At this valve position liquid fills the passageways 516, 515 and flows into the 50 chamber 481 which has just been vacuumized as previously described. The liquid in the chamber 481 is now trapped ready for quick filling of the can.

Filling the can

55

At station C (Fig. 1) the valve is moved another 90°, this time coming into the position illustrated in Figs. 35 and 36 for the filling step. At this station the intermediate ring 382 is cut 60 away on its inner face to provide a notch 521 which, like the other two notches 391, 505 permits clearance for turning of the block 345. This time the projection 509 turns into the notch 521.

The spider 346 (Figs. 1 and 22) is provided with a third finger 522 which is just in advance of the finger 506 and in the same horizontal plane. This finger passes into engagement with an actuating finger 523 secured to the intermediate ring 382 and extending out into the path of travel of the finger and the third quadrant movement of the valve is thus effected. The fourth side of the locking block 345 (indicated by the numeral 524 Figs. 2 and 3) is now presented to the inner faces of the rings 378 and 382 and the valve is 75

held against forward or backward movement as before.

In the valve position of Figs. 35 and 36 the chamber 481 provides the connection between the tank and the vacuumized can by passing over a nearly vertical passageway 526 cut through the body 241. The lower end of the passageway connects with the upper end of an inclined passage 527 extending downwardly through the topper 255 and terminating just inside of the ring 253.

The forward end of the chamber 481 first passes over the opening 526 at about the middle of the turning of the valve 331 at station C and therefore the liquid from the tank 53 immediately flows through the passageways 516, 515, chamber 481 and passageways 526, 527 into the can and continues as the valve comes to its position of rest. This filling is very rapid since a substantial vacuum is in the can and atmosphere is at all time pressing down on the surface of the liquid in the tank.

It will be recalled that a given quantity of air at atmospheric pressure was introduced into the can and locked off as a part of the liquid fill control previously referred to. During the passage of the liquid into the can from the tank this air confined within the filling head and within the top of the can is compressed as the space previously occupied by it fills with syrup.

There comes a time when this compressed air again equals atmospheric pressure or a little in excess of it to overcome the hydrostatic head of the higher liquid level in the tank and when such a point is reached a balance takes place and the flow of liquid ceases.

The height to which the liquid rises in the can depends entirely upon the amount of air in the can, as determined by the volume of air stored in the cylinder 469 as previously described. Each can passing through the machine is thus evenly filled. The valve 331 is again actuated and makes its fourth or final quadrant of movement as it is shifted back to its original position of Fig. 29.

Restoring filled can to atmosphere

This turning of the valve takes place in a fourth station D (Fig. 1). The lower ring 378 is cut away to provide a notch 535 which allows for clearance of the projection 377 of the locking block 345. Spider 346 is provided with a fourth finger 536 (Figs. 1 and 22) which is in the same plane as fingers 506, 522 and is radially located between the fingers 522, 371. This fourth finger is engaged by an obstruction illustrated in detail in Fig. 14 which comprises a U-shaped strap 541 which extends over and outside of the three rings 378, 382, 384 and is secured to the under side of the lower ring 378 by a bolt 542.

The upper rim of the housing shell 304 is slotted at 543 to provide clearance for this strap. The upper leg of the strap is in the path of travel of the finger 536 of the valve spider and upon engagement the valve rotates through its final movement of 90°.

It will be recalled that the rings 378, 382 and 384 are clamped in fixed position upon the brackets 305 (illustrated in detail in Fig. 7). With the clamps 385 loosened the valve actuating members 507, 523 and 541 (Fig. 1) may be individually shifted to change the timing of a particular valve movement, this being done by moving the ring on which the associated actuating member is mounted. This construction allows for a simple adjustment of valve actions and a considerable time variation for adjustment may

thus be had for different vacuumizing, fill controlling, and filling periods.

In this fourth movement of the valve the chamber 481 is locked off with its enclosed liquid, there being no connections with the chamber as best shown in Fig. 29. Other than this the other openings in the body 241 and in the valve 331 and the tube 467 and cylinder 469 are open to atmosphere as previously described in connection with Figs. 29 and 32 and the filled can is in condition to be removed from the filling head. The can is lowered just after passing station D, its upper edge leaving the rubber 252 as shown in Fig. 37.

Can discharge

15

Immediately after leaving station D the can support unit 72 lowers, carrying with it the filled can 75. In lowered position, can and support move adjacent a discharge starwheel 551 (Figs. 4 and 5) which is mounted upon the upper end of the vertical shaft 142. This starwheel is provided with a series of pockets and the filled can resting on the platform 225 of the supporting unit 72 engages within one of the pockets.

The rotating starwheel 551 moves with the can and carries the latter against a circular guide rail 552 which is preferably connected with the entrance guide rail 206. Continued rotations of the turret 51 and the starwheel 551 sweep the can off of its support and carry it over the upper surface of the table 134 which at this position is bolted to the frame 144. The starwheel moves the can around a circular path of travel, being guided by the rail 552. From this point the can may be discharged into any suitable position.

In the drawings there is illustrated a feeding-in disc 555 (Figs. 1 and 5) of a vacuum seaming machine designated generally by the numeral 556. The disc 555 may be associated with timing and feeding fingers 557 of any suitable construction, this type of device being well known in the can seaming art. A circular guide rail 558 preferably directs the can, after being received in the feeding fingers 557, into a vacuum chamber supported by the base 67 of the double seaming machine.

Sometimes it happens that a piece of fruit, for example, sticks to the bottom of the topper 255 when the filled can is being lowered from the filling head and although it is a rare occurrence provision is made for sweeping it off and back into the can as the can comes into the starwheel 551. For this purpose a blade 561 (Figs. 4 and 5) is formed with a vertical foot 562 which is secured to the outer skirt section of the cam 302. The top edge of the can passes just below this blade and the filling head passes just above and any fruit striking against the bar falls into the can.

Liquid supply for tank

The liquid for the tank 53 is introduced through a liquid housing 571 (Figs. 4 and 11) which is carried on the pipe 293. For this purpose the housing 571 is bolted to a bracket 572 which is formed with a sleeve section 573 having sliding engagement on the pipe. The sleeve 573 along one side is slit at 574 and a clamping bolt 575 with a handle 576 is used to tightly clamp the bracket 572 in a predetermined vertical position.

Provision is made for easy adjustment up and down of the bracket 572 and the housing 571. The weight of the bracket and housing together with parts carried thereby is counter balanced

75

so that its vertical movement is rendered easy when the clamping parts 575, 576 have been released.

The lower end of sleeve 573 is grooved at 578 and a second shorter sleeve 579 also provided with a similar groove 581 is also located on the pipe directly beneath the bracket sleeve. A split clamping ring 582 (Figs. 4 and 19) having ridges which extend into the grooves 578, 581 connects the members 573 and 579 in a joint which allows rotative movement of the bracket 572 relative to the sleeve 579. The split sections of the ring are united by bolts 583.

A headed and shouldered bolt 585 (Figs. 4 and 18) extends across the sleeve 579 and supports a block 586 which is located inside of the pipe 293. This block is held in central position on the bolt by a bushing 587 located on one end of the bolt and opposite to its shoulder. The bushing extends through one wall of the sleeve 579 and a washer 588 and nut 589 clamp the bushing in place. The pipe 293 is slotted on opposite sides at 591 and the bolt 585 rides freely within these slots when the bracket 572 is moved up and down on the pipe 293 and the sleeve 579 and block 586 are held from turning.

The block 586 carries a cap 595 in which the ends of a pair of wire cables 596 are located. These cables extend upwardly from the cap and pass upwardly over a pair of idler pulleys 597 thence down along the inside of the pipe and on opposite sides of block 586 and cap 595. Pulleys 597 turn freely on a pin 598 carried in a projection 599 formed on a pipe cap 601. This cap rests upon and closes the upper end of the pipe. The lower ends of the cables are connected to the upper end of a counter weight 602 hanging free within the pipe and which is of sufficient weight to substantially balance the weight of the bracket 572, housing 571 and parts carried thereby.

Provision is made for manually raising and lowering the block 586 and with it the bracket 572 and housing 571. For this purpose a rack 605 (Figs. 4, 17 and 18) is bolted to the block and extends downwardly within the pipe 293. Half tubular shells 607, 608 are bolted together at 609 and surround the pipe 293 directly below the sleeve 579.

Shell 608 is bulged outwardly at 611 and a part projects inwardly through an opening 612 cut in one side of the pipe 293. A stub shaft 615 is rotatably mounted within extension 611 and its inner end carries a pinion 616 which meshes with the teeth of the rack 605. The outer end of the shaft carries a crank handle 617 by which the shaft and the pinion are rotated. By turning the handle 617 the block 586 and all parts carried thereby are moved up or down as desired, the rack 605 passing freely within a clearance groove 618 formed in the weight 602.

The liquid for the supply tank 53 enters the housing 571 through a supply pipe 621 (Figs. 4 and 11) which may communicate with any suitable source of liquid supply. This pipe is threadedly engaged in the top of the housing and its lower end communicates with a valve chamber 622 partially set off by a reentrant casing 623 of the housing 571.

An opening 624 directly beneath and in alignment with the supply pipe 621 is closed by a cap 625 formed with a hand nut 626 which threadedly engages the housing wall. The cap 625 extends into the chamber 622 as a cage section 627 and a wire mesh or screen 628 is carried in the

cage. Liquid coming in through the supply pipe 621 must pass through the screen 628 as it enters the chamber 622 and any foreign matter is prevented from entering the chamber.

The casing 623 is cut through vertically at 631, 632 in aligned valve openings, the surrounding upper walls of which are formed as valve seats 633. A double valve 635 is located in the valve openings and valve heads 636, 637 formed in the valve, engage the valve seats and close the valve openings when the valve is in its lowered position.

When in raised position, valve 635 permits flow of liquid from the valve chamber 622 into a chamber 641 enclosed in the interior of the housing 571. Liquid thence flows into a discharge pipe 642 formed as an integral part of the housing 571 and which extends downwardly into the tank 53. With the valve 635 open liquid flows from the source of supply through the pipe 621, screen 628, chamber 622, valve openings 631, 632, chamber 641 and pipe 642 into the tank 53.

Liquid level control

Provision is made for keeping a substantially uniform level of liquid within the supply tank and this is controlled by a float 651 (Figs. 4 and 11). This float is secured to a vertical pipe 652 which surrounds the pipe 642 being considerably larger in diameter. Movement of the float 651 affects the valve 635 and controls the closing and opening of the valve ports 631, 632, shutting off the liquid supply when the level of the liquid in the tank 53 reaches a predetermined height.

A vertical rod 653, formed with a head 654 is located on the vertical center of the tank. The rod head 654 rests upon the tank valve 405, being loosely confined within a cap 655 which is secured to the tank valve. The rod 653 extends upwardly through the center of the float pipe 652 and the housing pipe 642 and projects through a bearing 656 formed in a housing cover 657 which is mounted on and bolted to the upper end of the housing 571. A collar 661 is pinned to the rod above the bearing 656.

Rod 653 forms a sliding support for a sleeve 662 which extends from the lower end of the chamber 641 through the pipe 642 and into the pipe 652. This sleeve has sliding movement within a pair of spaced spider brackets 663 carried on the inside of the pipe 642. These bearings operate to steady the sleeve during its vertical movement by holding it in proper alignment on the rod 653.

The sleeve 662 at its lower end is clamped in a spider 665 carried on the interior of the pipe 652. Lock nuts 666 threaded on the sleeve are used for this purpose. Movement of the float 651 and its pipe 652 causes a corresponding movement of the sleeve 662.

The upper end of the sleeve 662 carries a threaded cap 667 which is formed with a pair of upwardly extending lugs 668 located on opposite sides of the rod 653 and pivotally connected at 669 to a link 671 which is pivotally connected at 672, to one end of a lever 673. This lever 673 is carried in the upper part of the chamber 641 and is pivoted on a pin 674 carried in the housing 571. The other end of the lever 673 is connected through a universal joint unit 675 with the upper end of the valve 635.

With a normal level of liquid within the tank 53 (Fig. 11) the float 651 through the sleeve connections described holds the valve 635 open and liquid passes from the chamber 622 into the cham- 75

ber 641 and on into the tank. With a higher liquid level and a higher position for the float the valve 635 is lowered and the valve parts 636, 637 tightly close off the openings between the chambers 622, 641. Such a position of the valve prevents further supply of liquid into the tank.

The present invention contemplates stopping the operation of the machine or preventing feeding of cans, etc., in the event that the liquid within the tank 53 falls below a predetermined minimum level where the liquid supply might become insufficient for properly filling the cans. In such a low level condition the float 651 will move downwardly to a position lower than that illustrated in Fig. 11 and the valve 635 will be further lifted to a more open position.

The end of lever 673 which is secured to the valve is then lifted, first into engagement with a pin 681 and then both lever and pin are raised. This pin is loosely supported in a web 682 formed in an auxiliary cap 683 which may be an integral part of the cover 657. When so raised the pin 681 rocks a bell crank lever 685 pivoted at 686 in the cap 683. The upper arm of the bell crank lever 685 in turn raises a push button 687 of an electric switch 688 located in a switch box 689 bolted on the cap 683 of the cover.

To prevent any liquid reaching the bell crank lever 685 and the switch 688 a flexible diaphragm 691 is stretched across the space in the cap 683 and between the lower arm of the bell crank lever 685 and the top of the pin 681. This diaphragm is sufficiently flexible to offer no resistance to the operation of the switch by the pin 681.

The switch 688 may be of any suitable or usual construction and operates to close an electrical circuit passing into the switch. Such an electrical circuit may be electrically connected with some part of the operating drive mechanism of the can feed or the apparatus so that in the event of closing of the circuit through the switch 688 such can feed or other suitable part of the apparatus (for example the drive shaft 157) will be affected so as to stop further operative movement.

Emptying and cleaning tank

In some cannery filling installations, frequent syrup changes are made and at such a time it is necessary to empty the tank 53 of its liquid and replace with another liquid. This is a simple operation in the instant apparatus and a syrup change can be effected quite rapidly. In preparing for such a change the supply of liquid coming through the pipe 621 is shut off and as the tank float 651 gets lower and lower it finally reaches a place where the switch 688 operates to shut down the machine. This is the danger signal.

With the vacuum off the valve 405 is lifted and the remaining syrup in the tank drains into the chamber 404 and flows on down into the vacuum trap 434. To lift the valve at such a time the clamp 576 (Fig. 4) of the bracket 572 is released and the crank handle 617 of the lifting device is actuated to raise the bracket 572.

When the tank 53 and syrup passageways are to be thoroughly cleaned, as for example at the end of the day's run, the float 651 and valve 405 are taken out of the tank and cleaning water and steam is forced through the syrup passages. In this case the valve 405, float 651, housing 571 and bracket 572 are lifted as before by operation of the crank handle 617 until all of these parts are above the rim of the tank 53.

When in raised position the bracket 572 is turned on the pipe 293 and the housing 571 and parts carried thereby are swung around to clear the tank, the lower grooved end of the bracket sleeve 573 turning within the split ring 582. 5 With the bracket parts swung to one side the tank 53 is accessible from the top.

As soon as the valve 405 is unseated for either a syrup change or a cleaning, liquid will flow into the chamber 404 (Figs. 4 and 11) and thence 10 down through the pipe 421, elbow 426, pipe 431, through the tubular connection 435 (Fig. 41) and into the liquid trap 434. Liquid is removed from the trap 434 in the following manner:

A double acting pump unit is used which includes a pump cylinder 701 (Figs. 38, 39 and 43) bolted to one wall of the liquid trap 434. The interior of cylinder 701 is connected to the interior of the trap by a passageway 702. The interior of the cylinder 701 is also connected with a 20 chamber 705 formed in a cylindrical member 706 secured to the bottom of the pump cylinder. A flanged pump washer 707 is clamped between the parts 701, 706 and its central opening provides a connecting passage between the chamber 705 and the chamber enclosed in the cylinder 701 (designated by the numeral 708). A 25 pump piston 711 acts within these chambers.

The member 706 is supported in a tubular shell 712 which is formed with an extension 713 bolted 30 to the base 65. The member 706 is formed with a laterally extending tubular part 715 which projects out through the shell 712. The end of this part is closed by a threaded cap 716 and a short neck 717 extends at right angles. 35

The piston 711 is adapted to move from its uppermost position (as shown in Fig. 39), where it is within the upper end of the chamber 708, downwardly through the washer 707 and into the lower chamber 705. Liquid from the trap 434 40 flows through the passageway 702 into the pump chamber 708. When the piston is raised clear of the washer 707 liquid flowing through the washer opening also fills the lower chamber 705.

There is a second connection, however, between the interior of the trap 434 and the chamber 705 which utilizes the part 715. This connection comprises a pipe 721 (Figs. 38 and 39) threaded secured in the wall of the trap adjacent its lower end and joined with a vertical 50 pipe 722 which in turn is connected with a horizontal pipe 723 (Figs. 1, 38 and 40). Pipe 723 connects through a check valve 724 with a pipe 725 connected with a T 726 in a horizontal pipe line 727 leading into the neck 717. Liquid flows 55 from the trap 434 through these pipes and into the chamber 705 when the piston is being raised.

The piston 711 moving down and passing into the washer 707 cuts off the pump chamber 708 from the chamber 705. As the piston 711 further 60 descends, the liquid in the chamber 705 is forced out through the parts 715, 717 and into the pipe line 727. A check valve 728 is located in this pipe line and permits only an outward flow of liquid. At this time the check valve 724 in the 65 pipe line 725 prevents any return flow of liquid back into the trap 434.

The pipe line 727 connects with a vertical pipe 731 (Figs. 1, 11 and 40) which leads back to the tanks or other supply for the syrup. In a favorite form of installation the different grades of syrup are carried in different tanks or vats usually located on the floor above the filling machine and suitable means is used by which the syrup from a particular tank is brought down 75

into the filling machine by connecting that tank with the supply pipe 621.

In like manner the pipe 731 is used to return the liquid back to the particular tank where it belongs when the apparatus is being emptied of a certain grade of syrup. This return of the liquid is effected by the pump. In the pipe line 731 at a position just above the upper rim of the tank 53, a lateral pipe 732 is connected, this pipe having a shut off valve 733 so that when the syrup is being returned to the floor above this valve is closed.

When the syrup has been emptied and pumped back into its tank the apparatus is again ready for operation with a new grade of syrup and the proper connections are made to carry the new liquid supply into the tank through the supply pipe 621. It is understood, of course, that the valve 405 has been replaced before flowing in the new syrup.

When the apparatus is to be cleaned it is desirable that a cleaning fluid, such as hot water, be flushed through the system and this is put into the tank 53 in any suitable manner. It flows down through the various pipes into the liquid trap 434. The valve 133 is opened and the water is pumped back through the pipe 731 and thence through the pipe 732. Pipe 732 preferably carries a vertical extension 734 which extends down into the top of the tank.

This arrangement makes the changing of the syrup and the cleaning of the apparatus an easy matter, it being only necessary to operate the pump and discharge the syrup into its storage tank or when cleaning the pump effects the proper circulation of cleaning fluid where it is needed. When the piston 711 rises the check valve 728 prevents back flow of the liquid through the pipe lines 727 and 731 and the pump then draws liquid from the trap through the check valve 724 and into the chamber 705. On the pumping stroke the check valve 728 permits flow of liquid through the pipe lines 727, 731, 732 and 734 and the check valve 724 prevents return of the liquid to the liquid trap 434.

The pump and the lateral pipe 732 are also used when the apparatus is operating. At such time the pipe 731 above the connection with the pipe 732 is closed off from above and the liquid which is trapped in the bottom of the liquid trap 434 is drawn into the pump chambers 705, 708 and is then returned to the top of the tank through the pipes 731, 732, 734.

The piston 711 may be raised and lowered in any suitable manner, there being illustrated in the drawings one form of control for this purpose. In this form the piston is provided with an inner body 741 (Fig. 39) which is carried on the lower reduced end 742 of a piston rod 743 which connects at its upper end with a centering block 744. The top of the cylinder 701 is closed by a head 745 which extends upwardly as a tubular housing 746 open along one side adjacent its top as a slotted section 747.

A stuffing box 748 located in the head 745 and surrounding the rod 743 provides the proper liquid-tight packing for this sliding joint. The block 744 slides loosely in the housing 746 and insures proper movement of the piston rod 743 in its vertical travel. The upper end of the housing 746 is closed with a cap 749 which also encloses a lock nut 750 threadedly engaging the upper end of the piston rod and holding the block 744 on the rod.

The slot 747 provides a clearance opening for

a slide block 751 (Figs. 38 and 39) bolted to one side of the block 744. A connecting link 752 is pivoted at one end to the block 751 by a stud 753 and the lower end of the link 752 is similarly pivoted on a stud 754 carried by a crank arm 755 formed on one end of a stub shaft 756. The shaft 756 is journaled in a bracket 757 which is mounted upon a shelf 758 projecting outwardly from the shell 712. The shaft 756 is designed to be rotated in any suitable manner to effect the desired reciprocating operation of the pump. Rotation of the shaft may be made through a gear 759 carried on the end of the shaft or any other suitable driving connection may be employed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A vacuum filling machine for cans comprising in combination, a filling head unit for filling liquid into cans, can feeding devices for bringing cans to said head unit, means communicating with a vacuum source for vacuumizing a can while in said head unit, cooperating instrumentalities for completely encircling a wall of said can to prevent collapse from outside atmosphere during vacuumizing, one of said instrumentalities being movable and the other stationary relative to a said can in the unit, and means for discharging a quantity of liquid through said head unit and into the vacuumized can.

2. A vacuum filling machine for cans comprising in combination, a filling head unit, can feeding devices for bringing cans adjacent said head unit, means for clamping a can in filling position in said head unit, means communicating with a vacuum source for vacuumizing a can while in said unit, cooperating instrumentalities for completely encircling a wall of said can to prevent collapse from outside atmosphere during vacuumizing, one of said instrumentalities being movable and the other stationary relative to a said can in the unit, a tank for containing a liquid located adjacent said filling head unit, and means for discharging a quantity of liquid from said tank through said head unit and into the vacuumized can.

3. A vacuum filling machine for cans comprising, in combination, a filling head unit for filling liquid into cans, a lifting device for positioning a can for filling in said head unit, means communicating with a vacuum source for vacuumizing a can while in said unit, a fixed jaw carried by said lifting device, and a movable jaw associated with said head unit, said jaws cooperating one with the other to provide instrumentalities for encircling a wall of said can to prevent collapse from outside atmosphere during vacuumizing.

4. A vacuum filling machine for cans comprising, in combination, a filling head unit for receiving a can and filling it with a liquid, means communicating with a vacuum source for vacuumizing a can while in said unit as an incident to said filling, a fixed jaw for engaging an outside wall of said can, and a movable jaw pivotally mounted in said head unit at a position above the said can therein for also engaging said

outside can wall and cooperating with said fixed jaw to prevent collapse of the can from outside atmosphere during vacuumizing.

5. A vacuum filling machine for cans comprising, in combination, a filling head unit for filling liquid into cans, a lifting device for positioning a can for filling in said head unit, means communicating with a vacuum source for vacuumizing a can while in said unit, a fixed jaw carried by said lifting device for engaging a wall of the can thereon, a movable jaw associated with said unit and pivotally mounted thereon, and cam means for lifting said movable jaw clear of said lifting device to permit insertion of a can thereinto, and for also bringing said movable jaw into engagement with the wall of said can on said lifting device whereby said jaws cooperate to prevent collapse of the engaged can from outside atmosphere during vacuumizing.

20 6. A vacuum filling machine for cans comprising, in combination, a filling head unit, a lifting device for placing a can in filling position in said head unit, means communicating with a vacuum source for vacuumizing said can while 25 in said unit, a fixed jaw carried by said lifting device and engaging a wall of said can, a movable jaw mounted on said head unit and adapted to be moved into can engaging position in cooperation 30 with said fixed jaw, said jaws providing can encircling instrumentalities for preventing collapse of the cans from outside atmosphere during vacuumizing, and means for introducing a liquid into said vacuumized can through said head unit while 35 the can is held by said instrumentalities.

35 7. A vacuum filling machine for cans comprising in combination, a liquid supply tank, filling heads mounted on said tank for filling liquid into cans, devices for clamping a can in a said head, a passageway in each head communicating with a source of vacuum, a combination air and liquid valve unit associated with each head for opening and closing connections between a clamped can and the source of vacuum and between said can and the liquid of said supply 40 tank, actuating devices for controlling operation of said valves with the resulting vacuumization and filling of said cans, and locking devices associated with each of said valve units for preventing inadvertent operation.

50 8. A vacuum filling machine for cans comprising in combination, a continuously revolving turret, a liquid supply tank mounted on said turret, filling heads mounted on said tank and adapted 55 to hold cans to be filled, a combination air and liquid valve unit associated with each head for opening communication when in one position between the interior of a can positioned in a said head and a source of vacuum and when in another 60 position between said can and the liquid of said supply tank, stationary rings encircling said tank and said turret and located outside of said filling heads, and means carried by each of said rings and positioned within the path of travel of said 65 valve unit for permitting selective adjustment of either or both of the vacuumizing and filling intervals.

9. A vacuum filling machine for cans comprising in combination, filling heads adapted to hold 70 cans to be filled, a combination air and liquid valve unit associated with each head for controlling vacuumizing and liquid filling of a said held can, stationary rings located outside of the path of travel of said filling heads, and a stop carried on each of said rings for operating said valve,

said rings being individually adjustable to change the time period for vacuumization and filling.

10. A vacuum filling machine for cans comprising in combination, filling heads adapted to hold cans to be filled, a combination air and liquid valve unit associated with each head for controlling vacuumizing and liquid filling of a said held can, stationary rings located outside of the path of travel of said filling heads, a stop carried on each of said rings for operating said valves, 10 and locking devices carried in said valve unit and cooperating with said rings for holding said valve against movement during the passage of its associated filling head between said stop positions.

15 11. A vacuum filling machine for cans comprising, in combination, filling heads adapted to hold cans to be filled, an air cylinder associated with each filling head, a combination air and liquid valve unit associated with each head for controlling vacuumizing and liquid filling of a said held can, means actuated by the presence of a can within a filling head for placing said valve in position for operation, and actuating devices for moving said valve to first connect the interior of a held can with vacuumizing means, then with 20 the interior of said air cylinder and finally with a liquid supply whereby the desired vacuumization and filling of said can is accomplished.

25 12. A vacuum filling machine for cans comprising, in combination, a rotary liquid supply tank, 30 means for rotating said tank, a plurality of filling heads mounted on said tank and adapted to hold can to be vacuumized and filled, each of said heads having a connection with the interior of said tank and with a source of vacuum, a valve in 35 said tank for normally separating the liquid in said tank from communication with the source of vacuum, and means for operating said valve to drain the liquid from said tank.

40 13. A vacuum filling machine for cans comprising, in combination, a liquid supply tank for receiving liquid from a source of liquid supply, a filling head communicating with said tank for filling liquid into cans, a valve in said tank for draining the liquid therefrom, and means for returning the liquid from said tank to said source of liquid supply.

45 14. A vacuum filling machine for cans comprising, in combination, a liquid supply tank for receiving liquid from a source of liquid supply, a filling head mounted on said tank and adapted to hold cans to be vacuumized and filled, said head having a connection with the interior of said tank and with a source of vacuum, a liquid trap connected with said supply tank, a valve in said 50 tank for separating the liquid in the tank from communication with the source of vacuum during filling of cans through said head, means for operating said valve to drain the liquid from said tank into said trap, and means for returning the liquid from said trap back to said source of liquid supply.

55 15. A vacuum filling machine for cans comprising, in combination, a liquid supply tank, a filling head mounted on said tank and adapted 65 to hold cans to be vacuumized and filled, said head having a connection with the interior of said tank and a connection with a source of vacuum, a valve located in said tank for separating the liquid in said tank from the source of vacuum, 70 a liquid trap connected with said tank and also connected to said source of vacuum, and means associated with said liquid trap for preventing passage of liquid from the said trap into the vacuum connections.

16. A vacuum filling machine for cans comprising, in combination, a rotary liquid supply tank, means for rotating said tank, a filling head mounted on said tank and adapted to hold cans to be vacuumized and filled, a valve controlled liquid and vacuum chamber disposed within said tank, said head having a connection with the interior of said chamber and thence with a source of vacuum, said chamber being adapted to be vacuumized when the valve is in one position and to hold liquid when the valve is in another position, a liquid trap connected to said source of vacuum, and means associated with said liquid trap for returning trapped liquid back into said tank.
17. A vacuum filling machine for cans comprising, in combination, a liquid supply tank, a filling head mounted on said tank and adapted to hold cans to be vacuumized and filled, said head having a connection with the interior of said tank and with a source of vacuum, a valve located in said tank for normally separating the liquid in the tank from the source of vacuum, a liquid trap connected with said tank and with said source of vacuum, and a liquid pump associated with said liquid trap for returning the liquid from said trap back into said tank.
18. A vacuum filling machine for cans comprising, in combination, a rotatably mounted liquid supply tank, means for rotating said tank, a filling head communicating with said tank for filling liquid into cans, a float device operating in the liquid within said tank for maintaining a predetermined liquid level, and means disposed above said supply tank and actuated by said float device for controlling the operation of the machine upon failure of a sufficient amount of liquid in said tank to supply said filling head.
19. A vacuum filling machine for cans comprising, in combination, a rotatably mounted liquid supply tank, means for rotating said tank, a filling head mounted on said tank and adapted to hold cans to be vacuumized and filled, said head having a connection with the interior of said tank and with a source of vacuum, a combination air and liquid valve rotatably mounted on said head for controlling vacuumizing and liquid filling of a said held can, can actuated means for placing said valve in position for operation only when a can is present within said filling head, and means for holding said valve in operating position on said head.
20. A vacuum filling machine for cans com-

prising, in combination, a liquid supply tank, a filling head mounted on said tank and adapted to hold cans to be vacuumized and filled, said head having a connection with a source of vacuum and a connection with the interior of said tank, a combination valve unit rotatably mounted on said head for selectively opening said vacuum and said tank connections for vacuumizing and filling a said held can, and an annular groove in said head disposed below the periphery of said valve for holding a liquid to seal the joint between said head and said valve unit.

21. In an apparatus for filling and seaming cans under vacuum and comprising a vacuum filling machine, a double seaming machine and can transfer devices therebetween: the combination with said vacuum filling machine of a liquid supply tank, a filling head mounted on said tank and adapted to hold cans to be vacuumized and filled, means communicating with a vacuum source for vacuumizing a can while in said filling head, cooperating instrumentalities for completely encircling a wall of said can to prevent collapse from outside atmosphere during vacuumizing, one of said instrumentalities being movable and the other stationary relative to a said can in the head, and means for discharging a quantity of liquid through said head and into the vacuumized can.

22. A vacuum filling machine for cans comprising, in combination, a syrup supply tank, a filling head mounted on said tank and adapted to hold cans to be vacuumized and filled, said head having vacuum passages therein and having connection with the interior of said tank and with a source of vacuum, a combination air and syrup valve rotatably mounted in said head and having a plane surface disposed in sealing engagement with a corresponding surface of said filling head, said valve having vacuum passages therein and adapted to control vacuumizing and liquid filling of a said held can and mounted for rotation on a vertical axis, the engagement between said valve and head including a liquid sealing groove disposed in said filling head below said valve, the periphery of said valve overhanging said groove, the engagement of said valve and filling head permitting the circulation of a small quantity of water through the vacuum passages in said head and in said valve during the vacuumization of the can to prevent crystallization of the syrup in said passages.

ROBERT LUTHI.
